CLAIM

The ornamental design for flying disc toy, as shown and described.

DESCRIPTION

FIG. 1 is a perspective view of the flying disc toy showing my design;

FIG. 2 is a top plan view thereof;

FIG. 3 is cross sectional elevation view thereof; and,

FIG. 4 is a front elevation view in which the rear elevation view is a mirror image of the front view.

FIG. 1

FIG. 2

FIG. 3

FIG. 4
